US00D873840S

(12) **United States Design Patent** (10) **Patent No.:** **US D873,840 S**
Smith et al. (45) **Date of Patent:** **** Jan. 28, 2020**

(54) **DISPLAY SCREEN OR PORTION THEREOF
WITH A GRAPHICAL USER INTERFACE**

(71) Applicant: **HULU, LLC**, Santa Monica, CA (US)

(72) Inventors: **Hansen Smith**, Los Angeles, CA (US);
John Couch, Topanga, CA (US); **Josh Nelson**, Los Angeles, CA (US)

(73) Assignee: **HULU, LLC.**, Santa Monica, CA (US)

(**) Term: **15 Years**

(21) Appl. No.: **29/695,070**

(22) Filed: **Jun. 14, 2019**

Related U.S. Application Data

(63) Continuation of application No. 29/589,978, filed on Jan. 5, 2017, now Pat. No. Des. 862,487.

CLAIM

We claim the ornamental design for a display screen or portion thereof with a graphical user interface, substantially as shown and described.

DESCRIPTION

The FIGURE is a front view of a display screen or portion thereof with a graphical user interface showing our new design.

The outermost broken line shows an environment, whereas the remaining broken lines show a display screen and elements of a graphical user interface. None of the broken lines form part of the claimed design.
